CHARLES JACOBY, OF CROTON-ON-HUDSON, NEW YORK.

ROTARY ENGINE.

1,130,168.

Specification of Letters Patent.

Patented Mar. 2, 1915.

Application filed January 22, 1913. Serial No. 743,629.

To all whom it may concern:

Be it known that I, CHARLES JACOBY, a citizen of the United States, and resident of Croton-on-Hudson, in the county of West Chester and State of New York, have invented certain new and useful Improvements in Rotary Engines, of which the following is a specification.

This invention relates to rotary engines, and its object is a simple form of valve mechanism that shall be effective and durable, and in which renewals of the several parts would be easy and inexpensive.

The several objects are attained by the means set forth in this specification when taken in connection with the accompanying drawings, in which like letters and numerals refer to similar parts throughout the several views.

Figure 1 shows an elevation of the engine in longitudinal section. Fig. 2 is a transverse elevation of the engine. Fig. 3 is a portion of the engine in section showing the ejection ports. Fig. 4 represents the inner face of one of the heads of the engine and exhaust cams. Fig. 5 represents one of the heads of the engine provided with the induction cams.

The engine comprises, as in Fig. 1, a base *d*, and a casing mounted thereon consisting of a ring *a* upon which are secured the heads *a*¹ *a*², each provided with long bearings *y* *y* with stuffing boxes *w* *w* for the shaft *t*. Upon the shaft is a head *c* to which are secured the disks *b* *b*¹, which together constitute the revolving head. The head is slotted on opposite sides for sliding plates *e* *e*, as in Figs. 1 and 2. The slides comprise rectangular plates, with stems *i* *i* upon their inner edges. Holes are bored in the head as at *j* *j*, from the base of the slots for the slides, to the central channel *u*. The stems *i* have a two-fold purpose: they steady the plates *e* in their slots, and steam pressure against their inner ends is relied upon to thrust the plates outward from their slots. The ring *a* with the heads *a*¹ *a*² constitute a casing in which the head revolves. The disks *b* *b*¹ are provided with expansion rings 5 to closely fit and make a steam-tight joint with the ring *a*, shown in Figs. 1 and 3, so that the heads *a*¹ *a*² have no part in making a steam-tight joint between the heads and the steam chambers *A* *A*¹: but hold the ring *a* in place and prevent longitudinal movement of the head and the shaft.

Within and upon opposite sides of the ring *a* projections *p* *p* are provided, and the head *c* is fitted to revolve within the projections while the disks *b* *b*¹ inclose the projections between them. The projections are provided with adjustable packing plates *g* *g* which can be manipulated by the screws *h* *h*. The projections are curved upon top and lower sides to meet the bore of the ring *a*. 65 As will be plain in Fig. 2, as the head is revolved and the projecting plates *e* approach the curving surfaces of the projecting parts *p* the plates will be forced within their slots in the head. The plates *e* operate within 70 the steam chambers *A* *A*¹ that are formed between the head *c*, the ring *a*, the disks *b* *b*¹, and the projections *p* *p* as shown in Fig. 2.

Steam induction ports to the chambers *A* *A*¹ are made thus: The shaft upon which 75 the revolving head is secured, is made hollow to a point central of the head, as at *f*, Fig. 1. A steam chamber *u* in the head, around the shaft, is connected with the bore in the shaft through perforations *o* in the 80 shaft. Steam is admitted to the shaft through the steam inlet pipe *7*. At suitable points in the head holes are bored laterally through the head for the insertion therein of sliding pins *1*, as in Figs. 1 and 2, the 85 pins constituting the induction valves of the engine. The pins, or valves as they will be termed, intersect the steam passages *l* *l* and close the passages, as in the lower cross-section in Fig. 2. Grooves are suitably provided in the valves, as at 2, Figs. 1 and 2, so that the valves in one position will close 90 the steam passages, but will open the passages when the valves are moved so as to bring the grooves therein coincident with 95 the passages. The valves move freely, and their length is greater than the width of the head, so that when one end of either valve is flush with the side of the head, the other end of the valve will project beyond the other side of the head, the length of the distance between the head and the outer plates, as shown in Fig. 2, so that pushing the valve in one direction will close a steam passage 100 and pushing it in the opposite direction will 105 open a steam passage, or vice versa.

As shown in Fig. 1, the valves are both in position to admit steam past them, and they are held in such position by the cam pieces 3 3, Figs. 1 and 5, that are fast upon the 110 heads *a*¹ *a*². While in this position it will be observed that the ends of the valves opposite

the cams project into the chamber a^3 . In the said chamber are two other cams 4, alternating with the cams 3 in the chamber a^4 , shown in Fig. 2 in broken lines, and in plan 5 in Fig. 4, and one is shown in Fig. 1. The cams 3 hold the valves in position for admitting steam as in Fig. 1, until about three-quarters of the length of the steam chambers are traversed by the plates e , when the 10 valves will be past the cams 3, and will at once be engaged by the opposite cams 4, which move the valves to shut off the steam. The steam will then follow the plates e expansively to the ends of the steam chambers, 15 where, just before the plates e are to be forced inwardly by the projections p , the plates will pass over eduction ports m m , Figs. 2 and 3, which constitute the exhaust ports of the engine.

20 In Fig. 3 the eduction ports are shown in cross-section, and also how the exhaust passage m^1 are cored through the ring a and through the head a^2 to the inlets n n in the chamber a^3 , both steam chambers exhausting into the same chamber, from which an exhaust pipe 8 is taken.

An important feature in the construction of the engine, is this: The plates e , with their piston-stems i can be made of standard 30 rolled steel stock, and then by adapting the slots in the head, and the holes j for the standards adopted, renewals after wear will be easily made at a minimum of cost. The same method is applicable to the renewal of the valves.

To simplify the general description of some of the parts of the engine, the revolving element, that is, the head c with the disks b b^1 and their attachments is designated the rotator, and the chambers a^3 a^4 as 40 cam chambers.

Having described my invention, what I

claim and desire to secure by Letters Patent, is—

The combination in a rotary engine of a 45 shaft, a rotator upon the shaft which comprises a head, with disks upon the sides of the head, the disks having the diameter of the part in which the rotator revolves, the shaft bored and perforated to constitute it a 50 steam inlet, an annular steam chamber in the head around the perforations in the shaft, steam passages in the head from the annular chamber to the periphery of the head, the head slotted and bored from the 55 base of the slots to the annular steam chamber, plates with piston stems slideable in the slots and bores in the head, longitudinal valves in the rotator intercepting the steam passages, grooves in the valves to coincide 60 with the steam passages, the valves longer than the length of the rotator and adapted to be pushed back and forth laterally in their bearings, a casing for the rotator comprising a ring with projections on its inner face 65 by means of which the sliding plates in the head in the rotator are actuated, heads upon the ring that support the shaft and provide cam chambers upon each side of the rotator, cams upon one of the heads for moving the 70 valves to admit steam, and cams upon the opposite head to act upon the said valves to cut off steam, ports adjacent to the projections in the ring leading through the ring and one of the heads to one of the cam 75 chambers, and an exhaust connection with said chamber.

Signed at Croton on Hudson, in the county of Westchester and State of New York this 9th day of December A. D. 1912. 80
CHARLES JACOBY.
